VARIABLE STROKE HAND PUMP

Otto M. Summers, Mount Gilead, Ohio, assignor
to H-P-M Development Corporation, a corpora-
tion of Delaware

Application July 5, 1943, Serial No. 493,507

3 Claims. (Cl. 103—38)

1

This invention relates to pumping mechanisms and in particular to hand operated hydraulic pumps.

An object of the invention is to provide a hand operated hydraulic pump wherein the stroke of the pump is shortened as the pressure developed by the pump is increased so that the mechanical advantage of the hand lever over the pumping mechanism is gradually increased in proportion to the increase in pressure developed by the pump.

Another object of the invention is to provide a pumping unit wherein the pumping mechanism is constructed and arranged as a unitary structure so that it can be removed and replaced in the pumping mechanism for service or repair.

Another object of the invention is to provide a hand actuated pumping unit that is a self contained mechanism in that the pumping unit and the reservoir for the same is contained within a single structure.

A still further object of the invention is to provide a hand operated pumping unit for producing hydraulic pressure that is capable of delivering a large volume of hydraulic fluid at a relative low pressure and which volume delivery is gradually reduced by the pumping mechanism as the pressure is increased on the delivery side of the pumping mechanism.

Another object of the invention is to provide a hydraulically operated manually actuated pumping unit in accordance with the foregoing object wherein the lever for actuating the pumping unit is gradually shortened so that the mechanical advantage of the lever over the pumping unit is gradually increased as the pressure increases.

A still further object of the invention is to provide a manually actuated pumping unit for producing hydraulic pressure wherein the discharge pressure developed by the pump is used to move the lever mechanism that operates the pump so as to reduce the centers between the lever actuating mechanism and the pumping unit in response to the increase in pumping pressure developed by the pump whereby to reduce the volume of fluid discharged by the pump and maintain the power requirement for actuating the pump substantially constant.

It is another object of the invention to provide a hand operated hydraulic pump in accordance with any of the foregoing objects wherein the point at which the lever actuating mechanism begins to increase its mechanical advantage over the pump is adjustably regulated.

2

Still another object of the invention is to provide a hand operated pumping mechanism for producing hydraulic pressure in accordance with any of the foregoing objects wherein the volume of fluid delivered by the pump is relatively large as long as the pressure against which the pump is operating is relatively low, but as the pressure increases the delivery of the hand operated pump will fall off so that when maximum delivery of pump pressure is being developed by the pump there will be the smallest volume delivery from the pump to meet the final high pressure requirements of a mechanism actuated thereby, but at this time the mechanical advantage of the manually actuating mechanism is the greatest so that the power requirement is no larger than when the pump was producing the lower pressure.

Still another object of the invention is to provide a piston pump that is constructed as a unit piece of equipment that may be inserted into a supporting mechanism and be actuated by any lever actuated device, whereby the piston pump mechanism may be removed and replaced at will without disassembling the entire pumping mechanism for replacement or repairs.

Another object of the invention is to provide a hand operated pump for producing hydraulic pressure in accordance with any of the foregoing objects that is particularly adapted for use in actuating the small services of an aircraft.

Further objects and advantages will become apparent from the drawings and the following description.

In the drawings:

35 Figure 1 is a cross-sectional view of the hand operated hydraulic pump of this invention shown in diagrammatic association with a retractable aircraft landing apparatus.

40 Figure 2 is a somewhat similar illustration of the arrangement of the hand operated pump as it would be placed in association with the pilot's seat of an aircraft.

45 In this invention the pump consists of a main reservoir chamber 10 that provides the supporting member for the pumping mechanism. The reservoir chamber 10 has an internal chamber 11 that receives a body of hydraulic fluid 12 adapted to be pumped by the pumping unit 13.

The reservoir chamber 11 has an opening 14 in the top wall thereof adapted to receive the piston pump unit 13 for insertion therethrough.

50 The piston pump unit 13 consists of a cylinder 15 that has an internal bore 16 for receiving a piston plunger 17. The piston plunger 17 has an enlarged head portion 18 that forms a shoulder

19. An enlarged internal bore 20 is provided in the upper portion of the cylinder bore 16 and receives a coiled spring 21 that is provided between the shoulder 19 and the bottom surface of the recess formed by the enlarged bore 20.

The head portion 18 of the piston plunger 17 is hollowed out to form the recess 22 in which there is positioned a hardened metal ball 23 that is supported on a plurality of smaller balls 24. The upper edge portion of the chamber 18 is flanged inwardly as indicated by the flange portion 24 in order to hold the hardened metal ball 23 in position within the cage formed by the recess portion 22.

The piston plunger 17 is provided with a plurality of grooves 25 around the portion thereof that reciprocates within the cylinder bore 16 to provide an oil seal and thereby prevent leakage of hydraulic fluid upwardly around the piston to the external portion of the reservoir chamber 10.

The cylinder 15 is provided with 1 or more check valves 26 that consist of a body or cage member 27 enclosed within a recess portion 28 in the cylinder 15 and sealed thereto by means of a resilient seal member 29. A fluid passage 30 is provided in the cage member 28 and is adapted to be closed by means of a ball check 31 that is spring pressed against a seat provided by the passage 30 by means of the spring member 32. As illustrated in the drawing two of these check valves 26 are provided for regulating the flow of hydraulic fluid to the cylinder bore 16 through the passage 33. These check valves open toward the cylinder bore 16 when the piston plunger 17 moves in an upward direction, whereby the check valves 26 act as suction valves for the piston plunger 17.

A discharge check valve 34 is provided in the bottom wall 35 of the cylinder 15, this bottom wall portion 35 has a threaded portion 36 that is adapted to be threaded into a threaded opening 37 in the bottom wall of the chamber 11 whereby to hold the pumping unit 13 in position within the chamber 11 and with the flange 38 on the cylinder 15 in engagement with the top wall of the reservoir chamber 10.

The check valve 34 consists of a ball check member 38 that is retained within a bore 39 that communicates with the cylinder bore 16 by means of the passage 40, the ball check 38 being retained on the seat formed by the passage 40 by means of the coiled spring 41.

The discharge port 40 and the check valve 38 controls the flow of fluid under pressure from the cylinder bore 16 as forced therefrom by the piston plunger 17, and communicates with a discharge pressure passage 43 that conducts fluid under pressure to the pressure line 44 that connects to a service of an aircraft to be hereinafter described.

The actuating lever for the piston pump 13 consists of a lever member 45 that is pivotally mounted by means of a pivot pin 46 upon the head 47 of a piston plunger 48. The piston plunger 48 is substantially smaller in diameter than the piston head 47 and is slidably positioned within a cylinder bore 49 provided in the chamber support member 10. The piston plunger member 48 is provided with a plurality of annular rings 50 around the same that retain oil therein and thus prevent high pressure fluid from seeping past the piston plunger 48. A wear plate 51 is secured to the actuating handle 45 by means of the cap screws 52 and is adapted to engage the large ball 23 of the piston pump unit

13 for actuating the piston plunger 17 when the actuating handle 45 is pivoted about the pin 46 in a stroking movement.

The cylinder 49, or the end chamber 55 thereof communicates with the high pressure discharge port 43 from the pumping unit 13 by means of the passage 56.

A retaining guide rod 57 is provided for engaging the head 47 upon which the lever arm 45 is pivoted for guiding the same when it reciprocates along the system reservoir chamber 10 toward the piston pump 13.

A stud 58 extends upwardly from the piston head 47 and has an eye 59 therein against which the head 60 in the end of a rod 61 rests, a spring 62 being provided with an internal bore 63 provided in the reservoir housing 10 and having one end thereof against the bottom wall of the bore 63 and the opposite end against a flanged collar member 64 threaded upon the end of the rod 61, whereby the head 60 on the rod 61 is retained against the eye 59 of the stud 58 to thereby normally hold the head 47 in position as illustrated in the drawing of Figure 1. The spring 63 therefore opposes movement of the head 47, and pressure from the discharge passage 43 enters the end chamber 55 of the cylinder 49 to urge the piston plunger 48 in a leftward direction as viewed in Figure 1.

A transverse passage 100 is provided in the piston 48 that is adapted to cooperate with a passage 101 in the chamber housing 10 whereby to control the maximum forward stroke of the piston 48 due to the application of pressure in the end chamber 55.

As illustrated in Figure 2 of the drawing the pumping unit of this invention is adapted for use on an aircraft and is positioned adjacent the pilot's seat so that he can use the hand pump in raising or lowering the retractable landing gear of the aircraft or to provide hydraulic pressure for operating other services on the aircraft as desired. The pumping unit would preferably be placed adjacent the floor of the aircraft with the handle 70 being positioned along side pilot seat 71, so that he could grasp the handle and move the same upwardly and downwardly to reciprocate the handle and thus provide stroke on the piston pump unit 13.

As illustrated in Figure 1 the hand operated pumping unit of this invention is adapted to supply fluid to either end of a hydraulic jack 90 that is provided for operating a retractable landing gear 91 provided on an aircraft. The hydraulic jack 90 has the pressure service lines 92 and 93 that are connected to a fluid flow control valve 94. The pressure discharge conduit 44 from the pressure line 43 of the pumping unit 13 is connected to the flow control valve so that pressure fluid can be delivered into either of the service lines 92 and 93 supplying the service jack 90. Also, a return line 95 is connected to the valve 94 so as to return fluid that is being discharged from the jack 90 when pressure fluid is being supplied to one side thereof. The discharge line 95 connects with the reservoir chamber 11 to return hydraulic fluid to the reservoir chamber after it has been used or served its purpose in the jack 90.

When operating a hydraulic surface such as the jack 90, it is particularly desirable that a large volume of hydraulic fluid be supplied to the jack under low pressure when the jack is beginning to retract the landing gear mechanism 75 into the aircraft. This provides for rapid re-

traction of the landing gear. As the landing gear begins to approach its final position in the aircraft as illustrated in the dot-dash line shown in Figure 1, the total volume of fluid required to operate the jack becomes less, but the pressure of the fluid is considerably higher. Therefore at this time it is possible to supply a lesser quantity of fluid to the jack 80 but at a higher pressure in order to complete the retraction of the jack.

If a standard type press pumping hand operated pumping mechanism was used in this particular construction and arrangement the pump handle would operate relatively easy at the beginning of the retraction period but it would take a tremendous effort on the part of the operator to operate the pump when the high pressure develops at the end of the operating period. Therefore it is an object of this invention to provide the hand operated pumping mechanism with a variable stroke of the plunger to vary the discharge of the fluid for reducing the same as the pressure thereof increases in the discharge line from the pump and to maintain the operation of the hand lever with a constant rate of applied pressure upon the hand lever by the operator of the mechanism regardless of the pressure that is being developed by the pump. In order to accomplish this feature the leverage between the pivot 46 and the ball 23 is gradually reduced by moving the pivot pin 43 toward the vertical center line of the ball 23, as the pump pressure increases thereby increasing the mechanical advantage of the hand lever 70 over the pumping unit 13 so that a constant effort applied upon the handle by the operator will operate the pumping unit to produce any desired pressure for operating a service.

In order to vary the leverage between the piston 46 and the ball 23, the high pressure discharge from the pumping unit 13 is discharged through the conduit 43 and the conduit 56 into the end chamber 55 of the cylinder 49, so that as the pressure increases in the chamber 55 it will overcome the resistance of the spring 62 and thereby force the piston 46 in a leftward direction, thus moving the head 27 and the pivot 46 in a leftward direction toward the ball 23.

It will therefore become apparent that the stroke of the pump will be decreased as the pivot 46 moves in a leftward direction, and in fact can be brought to a substantially neutral position if the pivot of 46 is placed directly in a vertical line over the ball 23. At the same time, the hand lever 70 is gaining a mechanical advantage over the pump 13 so that the pressure being developed by the pump 13 shall not require any greater operating effort on the part of the operator when producing a high pressure than when it is producing a low pressure.

To adjust the point at which the pivot 46 begins to move in the leftward direction, the tension of the spring 62 is controlled by the initial compression placed thereon by adjusting the collar 64 upon the rod 61.

A shut-off valve rod 80 is provided in the passage 43 and has a ball 81 on the end thereof adapted to cooperate with the fitting 82 to form a valve. The opposite end of the rod 80 is engaged by an actuating member 83 that is threaded in the fitting member 84 secured within the wall of the reservoir chamber 10. Rotation of the member 83 will force the ball 81 against the fitting 82 and thereby close the discharge line 44 and retain pressure therein in order to hold

a pressure in this line should it become desirable to do so. A suitable hand lever 85 can be provided for operating the actuated member 83.

While the apparatus disclosed and described herein constitutes a preferred form of the invention, yet it is to be understood that the device is capable of mechanical alteration without departing from the spirit of the invention, and that all such modifications as fall within the scope of the appended claims are intended to be included herein.

Having thus fully described my invention, what I claim as new and desire to secure by Letters Patent is:

15. 1. A hydraulic pump comprising a cylinder and a piston reciprocable therein, a lever for reciprocating said piston and engaging the same intermediate the ends of the lever to form a fulcrum for said lever and to actuate the piston through the said fulcrum, a second reciprocable piston means, pivot means connecting one end of said lever to an end of said second piston means, the opposite end of said lever being free, and resting freely on said first-named piston, and being actuated to reciprocate said piston, means for supporting said one end of said lever adjacent to said pivot means and permitting free sliding movement of said lever whereby said piston last-named and said lever have a straight line movement with relation to each other as said lever slides on said piston first-named resilient means for holding said pivot means in a predetermined normal position to obtain a maximum spacing between said pivot means and the fulcrum of said lever means on said piston, and means for conducting fluid under pressure from the discharge side of the pump to said second piston means to actuate the same to overcome said resilient means and move said pivot means toward said piston to shorten the leverage between said pivot means and the fulcrum of said lever on said piston in response to the pressure increase of said pump to increase the stroke of said lever for maintaining the same stroke of said piston.
20. 2. A hydraulic pump comprising a cylinder and a piston reciprocable therein, a lever for reciprocating said piston and engaging the same intermediate the ends of the lever to form a fulcrum for said lever and to actuate the piston through the said fulcrum, a second reciprocable piston means, pivot means connecting one end of said lever to an end of said second piston means, the opposite end of said lever being free, and being actuated to reciprocate said piston, means for supporting said one end of said lever adjacent to said pivot means and permitting free sliding movement of said lever whereby said piston last-named and said lever have a straight line movement with relation to each other as said lever slides on said piston first-named, resilient means for holding said pivot means in a predetermined normal position to obtain a maximum spacing between said pivot means and the fulcrum of said lever on said piston, and means for conducting fluid under pressure from the discharge side of the pump to said second piston means to actuate the same to overcome said resilient means and move said pivot means toward said piston to shorten the leverage between said pivot means and the fulcrum of said lever on said piston in response to the pressure increase of said pump to increase the stroke of said lever for maintaining the same stroke of said piston.
25. 3. A hydraulic pump comprising a cylinder and a piston reciprocable therein, a lever for reciprocating said piston and engaging the same intermediate the ends of the lever to form a fulcrum for said lever and to actuate the piston through the said fulcrum, a second reciprocable piston means, pivot means connecting one end of said lever to an end of said second piston means, the opposite end of said lever being free, and being actuated to reciprocate said piston, means for supporting said one end of said lever adjacent to said pivot means and permitting free sliding movement of said lever whereby said piston last-named and said lever have a straight line movement with relation to each other as said lever slides on said piston first-named, resilient means for holding said pivot means in a predetermined normal position to obtain a maximum spacing between said pivot means and the fulcrum of said lever on said piston, and means for conducting fluid under pressure from the discharge side of the pump to said second piston means to actuate the same to overcome said resilient means and move said pivot means toward said piston to shorten the leverage between said pivot means and the fulcrum of said lever on said piston in response to the pressure increase of said pump to increase the stroke of said lever for maintaining the same stroke of said piston.
30. 4. A hydraulic pump comprising a cylinder and a piston reciprocable therein, a lever for reciprocating said piston and engaging the same intermediate the ends of the lever to form a fulcrum for said lever and to actuate the piston through the said fulcrum, a second reciprocable piston means, pivot means connecting one end of said lever to an end of said second piston means, the opposite end of said lever being free, and being actuated to reciprocate said piston, means for supporting said one end of said lever adjacent to said pivot means and permitting free sliding movement of said lever whereby said piston last-named and said lever have a straight line movement with relation to each other as said lever slides on said piston first-named, resilient means for holding said pivot means in a predetermined normal position to obtain a maximum spacing between said pivot means and the fulcrum of said lever on said piston, and means for conducting fluid under pressure from the discharge side of the pump to said second piston means to actuate the same to overcome said resilient means and move said pivot means toward said piston to shorten the leverage between said pivot means and the fulcrum of said lever on said piston in response to the pressure increase of said pump to increase the stroke of said lever for maintaining the same stroke of said piston.
35. 5. A hydraulic pump comprising a cylinder and a piston reciprocable therein, a lever for reciprocating said piston and engaging the same intermediate the ends of the lever to form a fulcrum for said lever and to actuate the piston through the said fulcrum, a second reciprocable piston means, pivot means connecting one end of said lever to an end of said second piston means, the opposite end of said lever being free, and being actuated to reciprocate said piston, means for supporting said one end of said lever adjacent to said pivot means and permitting free sliding movement of said lever whereby said piston last-named and said lever have a straight line movement with relation to each other as said lever slides on said piston first-named, resilient means for holding said pivot means in a predetermined normal position to obtain a maximum spacing between said pivot means and the fulcrum of said lever on said piston, and means for conducting fluid under pressure from the discharge side of the pump to said second piston means to actuate the same to overcome said resilient means and move said pivot means toward said piston to shorten the leverage between said pivot means and the fulcrum of said lever on said piston in response to the pressure increase of said pump to increase the stroke of said lever for maintaining the same stroke of said piston.
40. 6. A hydraulic pump comprising a cylinder and a piston reciprocable therein, a lever for reciprocating said piston and engaging the same intermediate the ends of the lever to form a fulcrum for said lever and to actuate the piston through the said fulcrum, a second reciprocable piston means, pivot means connecting one end of said lever to an end of said second piston means, the opposite end of said lever being free, and being actuated to reciprocate said piston, means for supporting said one end of said lever adjacent to said pivot means and permitting free sliding movement of said lever whereby said piston last-named and said lever have a straight line movement with relation to each other as said lever slides on said piston first-named, resilient means for holding said pivot means in a predetermined normal position to obtain a maximum spacing between said pivot means and the fulcrum of said lever on said piston, and means for conducting fluid under pressure from the discharge side of the pump to said second piston means to actuate the same to overcome said resilient means and move said pivot means toward said piston to shorten the leverage between said pivot means and the fulcrum of said lever on said piston in response to the pressure increase of said pump to increase the stroke of said lever for maintaining the same stroke of said piston.
45. 7. A hydraulic pump comprising a cylinder and a piston reciprocable therein, a lever for reciprocating said piston and engaging the same intermediate the ends of the lever to form a fulcrum for said lever and to actuate the piston through the said fulcrum, a second reciprocable piston means, pivot means connecting one end of said lever to an end of said second piston means, the opposite end of said lever being free, and being actuated to reciprocate said piston, means for supporting said one end of said lever adjacent to said pivot means and permitting free sliding movement of said lever whereby said piston last-named and said lever have a straight line movement with relation to each other as said lever slides on said piston first-named, resilient means for holding said pivot means in a predetermined normal position to obtain a maximum spacing between said pivot means and the fulcrum of said lever on said piston, and means for conducting fluid under pressure from the discharge side of the pump to said second piston means to actuate the same to overcome said resilient means and move said pivot means toward said piston to shorten the leverage between said pivot means and the fulcrum of said lever on said piston in response to the pressure increase of said pump to increase the stroke of said lever for maintaining the same stroke of said piston.
50. 8. A hydraulic pump comprising a cylinder and a piston reciprocable therein, a lever for reciprocating said piston and engaging the same intermediate the ends of the lever to form a fulcrum for said lever and to actuate the piston through the said fulcrum, a second reciprocable piston means, pivot means connecting one end of said lever to an end of said second piston means, the opposite end of said lever being free, and being actuated to reciprocate said piston, means for supporting said one end of said lever adjacent to said pivot means and permitting free sliding movement of said lever whereby said piston last-named and said lever have a straight line movement with relation to each other as said lever slides on said piston first-named, resilient means for holding said pivot means in a predetermined normal position to obtain a maximum spacing between said pivot means and the fulcrum of said lever on said piston, and means for conducting fluid under pressure from the discharge side of the pump to said second piston means to actuate the same to overcome said resilient means and move said pivot means toward said piston to shorten the leverage between said pivot means and the fulcrum of said lever on said piston in response to the pressure increase of said pump to increase the stroke of said lever for maintaining the same stroke of said piston.
55. 9. A hydraulic pump comprising a cylinder and a piston reciprocable therein, a lever for reciprocating said piston and engaging the same intermediate the ends of the lever to form a fulcrum for said lever and to actuate the piston through the said fulcrum, a second reciprocable piston means, pivot means connecting one end of said lever to an end of said second piston means, the opposite end of said lever being free, and being actuated to reciprocate said piston, means for supporting said one end of said lever adjacent to said pivot means and permitting free sliding movement of said lever whereby said piston last-named and said lever have a straight line movement with relation to each other as said lever slides on said piston first-named, resilient means for holding said pivot means in a predetermined normal position to obtain a maximum spacing between said pivot means and the fulcrum of said lever on said piston, and means for conducting fluid under pressure from the discharge side of the pump to said second piston means to actuate the same to overcome said resilient means and move said pivot means toward said piston to shorten the leverage between said pivot means and the fulcrum of said lever on said piston in response to the pressure increase of said pump to increase the stroke of said lever for maintaining the same stroke of said piston.
60. 10. A hydraulic pump comprising a cylinder and a piston reciprocable therein, a lever for reciprocating said piston and engaging the same intermediate the ends of the lever to form a fulcrum for said lever and to actuate the piston through the said fulcrum, a second reciprocable piston means, pivot means connecting one end of said lever to an end of said second piston means, the opposite end of said lever being free, and being actuated to reciprocate said piston, means for supporting said one end of said lever adjacent to said pivot means and permitting free sliding movement of said lever whereby said piston last-named and said lever have a straight line movement with relation to each other as said lever slides on said piston first-named, resilient means for holding said pivot means in a predetermined normal position to obtain a maximum spacing between said pivot means and the fulcrum of said lever on said piston, and means for conducting fluid under pressure from the discharge side of the pump to said second piston means to actuate the same to overcome said resilient means and move said pivot means toward said piston to shorten the leverage between said pivot means and the fulcrum of said lever on said piston in response to the pressure increase of said pump to increase the stroke of said lever for maintaining the same stroke of said piston.
65. 11. A hydraulic pump comprising a cylinder and a piston reciprocable therein, a lever for reciprocating said piston and engaging the same intermediate the ends of the lever to form a fulcrum for said lever and to actuate the piston through the said fulcrum, a second reciprocable piston means, pivot means connecting one end of said lever to an end of said second piston means, the opposite end of said lever being free, and being actuated to reciprocate said piston, means for supporting said one end of said lever adjacent to said pivot means and permitting free sliding movement of said lever whereby said piston last-named and said lever have a straight line movement with relation to each other as said lever slides on said piston first-named, resilient means for holding said pivot means in a predetermined normal position to obtain a maximum spacing between said pivot means and the fulcrum of said lever on said piston, and means for conducting fluid under pressure from the discharge side of the pump to said second piston means to actuate the same to overcome said resilient means and move said pivot means toward said piston to shorten the leverage between said pivot means and the fulcrum of said lever on said piston in response to the pressure increase of said pump to increase the stroke of said lever for maintaining the same stroke of said piston.
70. 12. A hydraulic pump comprising a cylinder and a piston reciprocable therein, a lever for reciprocating said piston and engaging the same intermediate the ends of the lever to form a fulcrum for said lever and to actuate the piston through the said fulcrum, a second reciprocable piston means, pivot means connecting one end of said lever to an end of said second piston means, the opposite end of said lever being free, and being actuated to reciprocate said piston, means for supporting said one end of said lever adjacent to said pivot means and permitting free sliding movement of said lever whereby said piston last-named and said lever have a straight line movement with relation to each other as said lever slides on said piston first-named, resilient means for holding said pivot means in a predetermined normal position to obtain a maximum spacing between said pivot means and the fulcrum of said lever on said piston, and means for conducting fluid under pressure from the discharge side of the pump to said second piston means to actuate the same to overcome said resilient means and move said pivot means toward said piston to shorten the leverage between said pivot means and the fulcrum of said lever on said piston in response to the pressure increase of said pump to increase the stroke of said lever for maintaining the same stroke of said piston.
75. 13. A hydraulic pump comprising a cylinder and a piston reciprocable therein, a lever for reciprocating said piston and engaging the same intermediate the ends of the lever to form a fulcrum for said lever and to actuate the piston through the said fulcrum, a second reciprocable piston means, pivot means connecting one end of said lever to an end of said second piston means, the opposite end of said lever being free, and being actuated to reciprocate said piston, means for supporting said one end of said lever adjacent to said pivot means and permitting free sliding movement of said lever whereby said piston last-named and said lever have a straight line movement with relation to each other as said lever slides on said piston first-named, resilient means for holding said pivot means in a predetermined normal position to obtain a maximum spacing between said pivot means and the fulcrum of said lever on said piston, and means for conducting fluid under pressure from the discharge side of the pump to said second piston means to actuate the same to overcome said resilient means and move said pivot means toward said piston to shorten the leverage between said pivot means and the fulcrum of said lever on said piston in response to the pressure increase of said pump to increase the stroke of said lever for maintaining the same stroke of said piston.

curved and another portion beyond said curve forming a handle.

3. A hydraulic pump comprising a cylinder and a piston reciprocable therein, a lever for reciprocating said piston and engaging the same intermediate the ends of the lever to form a fulcrum for said lever and to actuate the piston through the said fulcrum, a second reciprocable piston means, pivot means connecting one end of said lever to an end of said second piston means, the opposite end of said lever being free, and resting freely on said first-named piston, and being actuated to reciprocate said piston, means for supporting said one end of said lever adjacent to said pivot means and permitting free sliding movement of said lever whereby said piston last-named and said lever have a straight line movement with relation to each other as said lever slides on said piston first-named, resilient means for holding said pivot means in a predetermined normal position to obtain a maximum spacing between said pivot means and the fulcrum of said lever on said piston, and means for conducting fluid under pressure from the discharge side of the pump to said second piston means to actuate the same to overcome said resilient means and move said pivot means toward said piston to shorten the leverage between said pivot means and the fulcrum of said lever on said piston in response to the pressure in-

crease of said pump to increase the stroke of said lever for maintaining the same stroke of said piston, said lever having a portion of its free end curved and another portion beyond said curve forming a handle, and passage means normally closed by said second piston means and opened by the second piston means upon a predetermined stroke of the second piston means to by-pass the fluid under pressure in the first passage means and thereby limit the stroke of the said second piston means.
